UNITED STATES PATENT OFFICE.

JOHN WILSON BROWN, JR., OF PHILADELPHIA, PENNSYLVANIA, ASSIGNOR
TO THE ENTERPRISE MANUFACTURING COMPANY, OF PENNSYLVANIA.

DESIGN FOR THE FRAME OF A CUTTING OR FORCING PRESS.

SPECIFICATION forming part of Design No. 18,359, dated June 5, 1888.

Application filed March 20, 1888. Serial No. 267,908. Term of patent 14 years.

To all whom it may concern:

Be it known that I, JOHN WILSON BROWN, Jr., a citizen of the United States, and a resident of Philadelphia, Pennsylvania, have invented a new and original Design for the Frame of a Cutting or Forcing Press, of which the following is a specification.

My design for the frame of a cutting or forcing press is fully shown in the accompanying drawings; and it consists, essentially, of a barrel having a stem forked at its lower end, substantially as described hereinafter.

In the accompanying drawings, Figure 1 is a perspective view of the press; Fig. 2, an end view of the same, and Fig. 3 a side view.

A is the body or barrel of the press, from which projects downwardly a stem, B, forked at the lower end, so as to form opposite bent legs b. An extension, b', of the stem B projects downward beyond the forked end of said stem, this extension being in a plane somewhat in the rear of the stem itself, and projecting forward at the lower end so as to terminate beneath the stem.

The barrel A of the press has at the top a hopper, a.

I claim—

The design for the frame of a cutting or forcing press, said design comprising the barrel having a downwardly-projecting stem forked at its lower end, and said stem having an extension in a different plane, which extension projects forward at its lower end, all substantially as described and shown.

In testimony whereof I have signed my name to this specification in the presence of two subscribing witnesses.
